DESIGN FOR A MEAT PACKING TABLE UNIT

Frank J. Bilek, Chicago, Ill., assignor to The Globe Company, Chicago, Ill., a corporation of Illinois

Application October 4, 1944, Serial No. 115,609

Term of patent 14 years

(Cl. D11—1)

To all whom it may concern:

Be it known that I, Frank J. Bilek, a citizen of the United States, residing at Chicago, in the county of Cook and State of Illinois, have invented a new, original, and ornamental Design for a Meat Packing Table Unit, of which the following is a specification, reference being had to the accompanying drawing, forming a part thereof.

Fig. 1 is a plan view of a meat packing table unit embodying my new design;

Fig. 2 is a front elevational view of the same; and

Fig. 3 is the side elevational view of the same viewed from the left-hand end of the combination.

I claim:

The ornamental design for a meat packing table unit, substantially as shown.

FRANK J. BILEK.
